Primary Examiner—Doris Clark

(57) **CLAIM**

I claim the ornamental design for a fence, as shown and described.

DESCRIPTION

FIG. 1 is a fragmented top perspective view of a fence showing my new design.

FIG. 2 is a fragmented front elevation view thereof.

FIG. 3 is a fragmented cross sectional view taken alone line 3—3 of FIG. 2.

FIG. 4 is a fragmented top perspective view of a second embodiment of a fence showing my new design.

FIG. 5 is a fragmented front elevation view thereof; and,

FIG. 6 is a fragmented cross-sectional view taken alone lined 6—6 of FIG. 5.

The claimed design is broken in the center for ease of illustration.
